UNITED STATES PATENT OFFICE.

JAMES PATRICK CLARK, OF CHICAGO, ILLINOIS.

ADJUSTABLE PIANO SEAT OR BENCH.

No. 843,584.

Specification of Letters Patent.

Patented Feb. 12, 1907.

Application filed October 5, 1905. Serial No. 281,479.

To all whom it may concern:

Be it known that I, JAMES PATRICK CLARK, a citizen of the United States, residing at Chicago, in the county of Cook and State of Illinois, have invented a new and Improved Adjustable Piano Seat or Bench, of which the following is a specification.

This invention relates to an adjustable bench for pianos or organs.

The object of the invention is to provide a bench having a supplemental movable top which can readily be raised and lowered.

The invention consists of the novel features of construction hereinafter described, pointed out in the claims, and shown in the accompanying drawings, in which—

Figure 1 is a perspective view of my bench. Fig. 2 is a partial side elevation and a partial longitudinal section. Fig. 3 is a section on the line 3 3 of Fig. 2, showing an inverted plan view of the bench-top. Fig. 4 is a detail perspective view of the rack-bar. Fig. 5 is a detail view of a casing in which the rack-bar works.

In these drawings, A represents a suitable bench of any size and design. A metal casing B has its upper portion formed cylindrically and threaded, as shown at B'. Two of these casings B are employed, one adjacent each end of the bench A, and the cylindrically threaded portion is passed upwardly through the top of the bench A and is held in place by a countersunk nut B². Each casing B has a lateral extension B³, and, as shown in the drawings, the casing B and extension B³ have square bores therein. The outer end of the extension B³ is closed by the perforated plate B⁴. A lever C is centrally pivoted beneath the bench A and midway the ends of the lever. On the under side of the top of the bench A are secured guide-brackets C' in alignment with the extensions B³ and the pivot-point of the lever C. Slightly-angled rods D are pivoted at their inner ends to the lever C and on opposite sides of the pivotal point of the said lever, and these rods work through the brackets C' and through the perforated plates B⁴ and extend one each into the extensions B³ of the casings B. Within the casings B' rods D, carrying bolt portions

D' and springs D², are arranged in the extensions and bear upon the said bolts. A supplemental table-top E is provided, and a metal plate E' is secured transversely upon the under side of the said top adjacent each end thereof, and each of the plates E' carries a depending rack-bar E². These rack-bars extend into and work vertically within the casings B, and the teeth of the rack-bars are engaged by the spring-pressed bolts D'. These bolts normally prevent the lowering of the top E. The top E can be raised without manipulating the lever C, and to lower the same it is only necessary to swing one end of the lever C out of its normal position, and both of the rods D will be moved inwardly toward the center of the table and the bolts D' withdrawn from engagement with the rack-bars E², and the top can then be lowered the desired distance. Upon releasing the lever C the springs D² will return the lever, rods D, and bolts D' to their normal position.

Having thus fully described my invention, what I claim as new, and desire to secure by Letters Patent, is—

1. In a device of the kind described, a bench, a supplemental top, casings, threaded at their upper ends into end portions of the bench, and arranged on the line of the major axis of the bench, said casings having laterally-extending casings, metal plates carried by the under side of the supplemental top, depending rack-bars formed integral with said plates, said bars working in the casings, and spring-actuated bolts, working in the lateral casings.

2. A device of the kind described, comprising a bench, casings carried thereby, said casings opening upwardly through the top of the bench, lateral extensions carried by the casings, a supplemental top, rack-bars carried by the top and working in the casings, spring-pressed bolts in the extensions of the casings adapted to engage the rack-bars, and means for simultaneously disengaging the said bolts.

JAMES PATRICK CLARK.
